UNITED STATES PATENT OFFICE.

WILLIAM E. FITCH, OF LOUISVILLE, KENTUCKY.

DESIGN FOR A FIREPLACE-FRONT.

SPECIFICATION forming part of Design No. 25,420, dated April 21, 1896.

Application filed February 27, 1896. Serial No. 581,076. Term of patent 3½ years.

To all whom it may concern:

Be it known that I, WILLIAM E. FITCH, a citizen of the United States, residing at Louisville, in the county of Jefferson and State of Kentucky, have invented and produced a certain new and original Design for Fireplace-Fronts, of which the following is a full, clear, and exact description.

The leading features of this invention are 10 conventionalized torches, leafy branches or sprays, and a wreath, and ribbons or streamers and a central medallion, arranged symmetrically to form a fireplace-frame and summer-piece of uniform and harmonious design.

15 The accompanying drawing illustrates my design in elevation.

The frame *a* has upon its pilasters *b* or styles the vertical torches, whose shanks are entwined by leafy branches or sprays and 20 from whose butts depend laterally-extending ribbons or streamers. The top rail *c* has a central wreath with laterally-extending ribbons or streamers, the said wreath being flanked by leafy branches or sprays rising 25 from the bottom of the wreath. A ribbon falls in a looped knot from the bottom of the wreath over into the summer-piece *d* and disappears behind the circular medallion *e*, there being laterally-extending streamers from 30 such knotted loop crossing the upper part of the summer-piece above the medallion. The

border of the medallion is of a conventionalized leafy pattern of circular form and curved cross-section, and within the border is a winged female figure, having the conventional attitude of flight, and with flowing drapery and with extended hands dropping flowers. Clinging to the back of this figure is a cherub holding a torch in an extended hand. At the bottom of the medallion are 35 streamers or ribbons extending across the summer-piece from side to side and represented as tied about the border. The medallion appears to be suspended from the wreath by the looped knot. 40

The design is cast in metal in high relief, but obviously it may be in low relief or intaglio. 45

What I claim is—

1. In a design for a fireplace-front, the 50 frame, substantially as shown and described.

2. In a design for a fireplace-front, the summer-piece, substantially as shown and described.

3. The design for a fireplace front, substantially as shown and described. 55

In testimony whereof I have hereunto set my hand this 25th day of February, A. D. 1896.

WILLIAM E. FITCH.
